UNITED STATES PATENT OFFICE.

SAMUEL E. BARLOW, OF DENVER, COLORADO.

DERRICK-CAR.

1,351,226.

Specification of Letters Patent. Patented Aug. 31, 1920.

Application filed March 1, 1920. Serial No. 362,274.

To all whom it may concern:

Be it known that I, SAMUEL E. BARLOW, a citizen of the United States, residing at the city and county of Denver and State of Colorado, have invented certain new and useful Improvements in Derrick-Cars; and I do declare the following to be a full, clear, and exact description of the invention, such as will enable others skilled in the art to 10 which it appertains to make and use the same, reference being had to the accompanying drawings, and to the characters of reference marked thereon, which form a part of this specification.

15 The object of this invention is to provide a derrick for railroad use which is sufficiently strong and heavy to handle a plurality of rails, instead of handling only a single rail at a time.

20 Briefly the invention comprises a heavy derrick platform adapted to be carried by an ordinary flat car, said platform being equipped with an engine, a boom, suitable hoisting cables, and power-operated tongs 25 so mounted upon the boom that swinging of said tongs when loaded will be reduced. In order to accomplish this last mentioned function successfully, the boom is varied somewhat in structure from the ordinary 30 type.

In the drawings:

Figure 1 is a side elevation showing the derrick mechanism mounted upon a flat car.

Fig. 2 is an end elevation of the power 35 tongs, as indicated by arrow 2 of Fig. 1.

Fig. 3 is a vertical section showing the structure of the derrick platform; and

Fig. 4 is a cross section on line 4—4 of Fig. 1.

40 An ordinary flat car 10 is shown, upon which is mounted the platform of the derrick. The latter comprises a horizontal bed 12, provided with cross timbers 14, to which are connected mountings 16, having journals 18, and heavy rollers 20, which support said derrick platform and permit the same to be moved upon the flat car. The rollers 20 are 45 of more or less massive construction, and so built that they will not readily break or crack. They comprise shafts 21, mounted in

said journal 18, end plates 22 and central castings 24, which are connected with said end plates 22 by means of bolts 25. Soft boiler plate 26 is provided about the peripheries of said parts 22 and 24 to form the 55 tread of said rollers, and the interior is filled with concrete 28. The casting 24 is grooved out at 30, as shown in Fig. 4, to receive a rail 32, mounted upon the flat car 10 for the purpose of maintaining the position of the derrick upon said flat car. These central castings 24 are also grooved to accommodate a cable 34, passing thereabout, and over pulleys 36 on the derrick platform, and thence to a drum 38, driven by 60 the engine 40. In this manner the cable 34 and drum 38 serve as means to move the derrick platform along the flat car and, if necessary, from one car to another. At the same time these parts also constitute a brake 70 for the derrick platform.

Mounted upon the end of the derrick platform, opposite the engine 40, is a framework 42 and a boom 44, which is pivoted at 46 to a block on the bottom of a vertical 75 post 48, pivoted at 50 in the top bar of the framework 42 and at 52 in the derrick platform 12. The post 48 carries a bull wheel 54, which turns upon a bearing 56 in the platform 12 and is driven by means of a 80 chain 58 by a small engine 60.

The outer end 62 of the boom 44 is offset, as shown, and is controlled by means of a link 64 and pulleys 66, operated through the medium of a cable 68, driven by a drum 85 70, connected with the engine 40. The cable 68 passes through said upright post 48 and is adapted to bear upon either of the pulleys 72 or the rollers 74 in said post, as shown in Fig. 4. The offset portion 62 of the boom is provided with a pair of pulleys 76, over which there passes a pair of cables 78, these cables being conducted over pulleys 80, supported by the top of the framework 42 and thence to a drum 81, controlled by the engine 40. 95

The power tongs comprise a pair of spaced jaws 82, mounted upon a common shaft 84, each set of jaws 82 being operated by cylinders 86, controlled through a double 100

air line 88, which runs to the engineer's station on the rear of the platform 12. The two pulleys 76 are spaced on the offset part 62 of the boom a distance greater than the 5 distance between the jaws 82, so that the lower ends of the cables 78 converge as they approach said power tongs. By this construction swinging of the tongs when loaded is reduced. By having the outer 10 portion 62 of the boom 44 offset from the body thereof, sufficient space is provided beyond said body 44 for the projecting ends of the rails.

It is to be noted particularly that the 15 rollers 22, constructed as herein disclosed, are sufficiently heavy to keep the derrick platform 12 securely anchored to the flat car 10, so that unusually heavy loads of rails may be handled by the derrick.

20 It will be apparent from the foregoing that this derrick car is a self-propelling, rail-loading machine of large capacity. The large number of rollers and their considerable length serve to distribute the 25 weight of the derrick car over the surface of the flat car so that the ordinary flat car, which is of relatively light construction, will be sufficiently strong to carry its load.

By using the power-operated tongs here 30 disclosed, which comprise the spaced jaws 82 and the spaced points of support 76, the center of gravity of the load may be more easily straddled and at the same time the load may be readily steadied without having 35 the center of gravity exactly between the jaws 82. This produces a structure which is quickly operated and capable of handling a heavy load at each operation.

The independent swinging engine 60 for 40 the boom, enables the boom to be swung more readily and desirably than if controlled from the hoisting engine 40.

Each of the drums 81 is independently 45 controllable so that the cables 78 may be moved separately or in unison. The jaws 82 are controlled through the air lines 88. In this way the tongs require no attendance whatever, all operations being controlled by the engineer at his station on the platform 60 12. Also this arrangement permits materials to be removed from slopes or where they are set at angles to the track. The tongs may be lowered with one set of jaws 82 below the other set, the lower set then 55 being positioned about the materials. If the latter are at an angle, the boom may be swung a little by engine 60, thus throwing the free jaws around, which are lowered and positioned about the materials. The jaws 60 are then closed and the usual hoisting operations follow.

I claim:

1. A derrick car, comprising a derrick platform and a series of long heavy rollers

disposed transversely under said platform 65 and journaled thereon.

2. A derrick car, comprising a derrick platform and a series of long heavy rollers disposed transversely under said platform 70 and journaled thereon, said platform having an engine thereon and a driving connection between the engine and said rollers.

3. A derrick car, comprising a derrick platform and a series of long heavy rollers disposed transversely under said platform 75 and journaled thereon, said rollers comprising axles having metal shells thereabout forming the roller treads, the interior of said rollers being filled with concrete.

4. A derrick car, comprising a derrick 80 platform and a series of long heavy rollers disposed transversely under said platform and journaled thereon, each of said rollers comprising an axle, end members thereon, a center casting, an outer shell forming a 85 tread, said shell, end members and casting being secured together, and the interior of the roller filled with concrete.

5. A derrick car, comprising a derrick platform and a series of long heavy rollers 90 disposed transversely under said platform and journaled thereon, each of said rollers comprising an axle, end members thereon, a center casting, an outer shell forming a 95 tread, said shell, end members and casting being secured together, and the interior of the roller filled with concrete, said center casting being grooved to receive a driving cable.

6. A derrick car, comprising a derrick 100 platform and a series of long heavy rollers disposed transversely under said platform and journaled thereon, each of said rollers comprising an axle, end members thereon, a center casting, an outer shell forming a 105 tread, said shell, end members and casting being secured together, and the interior of the roller filled with concrete, said center casting being grooved to travel on a rail on a flat car.

7. In combination, a flat car, and a derrick car thereon comprising a derrick platform having a series of heavy rollers positioned thereunder and journaled thereon, resting upon the flat car and having a length approaching the width of said flat car.

8. A derrick car comprising a derrick platform, having a series of heavy rollers positioned thereunder and journaled thereon, an engine on one end thereof and a boom 120 on the other end carrying a pair of heavy power-operated tongs.

9. A derrick car having a series of heavy rollers thereunder journaled thereon, and having at one end a boom with an offset end, 125 said offset end carrying a pair of heavy power-operated tongs.

10. A derrick car, having a series of heavy

rollers thereunder and journaled thereon, and a boom mounted on one end thereof, said boom having an offset end and carrying adjacent the end thereof a pair of spaced 5 pulleys, cables passing over said pulleys and supporting the upper portions of a pair of rigidly connected power-operated tongs, said

pulleys being farther apart than said upper portions of said tongs for the purpose of reducing swinging of a load carried by the 10 tongs.

In testimony whereof I affix my signature.

SAMUEL E. BARLOW.
